STEAM-ELECTRIC FLATIRON

Ernest F. Thomson, Tuckahoe, N. Y., assignor to
Casco Products Corporation, Bridgeport, Conn.,
a corporation of Connecticut

Application May 26, 1949, Serial No. 2,899

Term of patent 14 years

(Cl. D49—6)

To all whom it may concern:

Be it known that I, Ernest F. Thomson, a citizen of the Dominion of Canada, subject of the King of Great Britain, and residing at Tuckahoe, county of Westchester, and State of New York, have invented a new, original, and ornamental Design for a Steam-Electric Flatiron, of which the following is a specification, reference being had to the accompanying drawing, forming part thereof.

Figure 1 is a side elevational view of a steam-electric flat iron, showing my new design.

Fig. 2 is a top or plan view of the flat iron shown in Fig. 1, and

Fig. 3 is a rear elevational view of the iron shown in Figs. 1 and 2.

I claim:

The ornamental design for a steam-electric flatiron, substantially as shown.

ERNEST F. THOMSON.
